GRAPHICAL RECORDER

Edward E. Austin, Pasadena, and Richard M. Kemplin,
Altadena, Calif., assignors to F. L. Moseley Co., a cor-
poration of California

Filed July 24, 1961, Ser. No. 66,044

Term of patent 14 years

(Cl. D26—14)

FIG. 1 is a perspective view of a graphical recorder showing our new design and illustrating the left side and front thereof; and

FIG. 2 is a perspective view to a reduced scale showing the right side and rear thereof.

The dominant features of our design reside in the portions shown in full lines and comprise the overhanging top portion and the bottom side portion along the front, the angle at which the front control panel is mounted, and the shape of the rear panel.

We claim:

The ornamental design for a graphical recorder as shown and described.
